LIQUID SLIP REGULATOR

Claude B. Huston, Schenectady, N. Y., assignor
to General Electric Company, a corporation of
New York

Application September 23, 1943, Serial No. 503,491

10 Claims. (Cl. 172—274)

This invention relates to apparatus for controlling induction motors; more particularly to liquid slip regulators, and it has for an object the provision of a simple, reliable, and improved device of this character.

Heretofore, liquid slip regulators have been equipped with alternating current torque motors for raising the movable electrodes. These torque motors were supplied from series current transformers connected in the primary circuit of the controlled induction motor.

The alternating current torque motors used in liquid slip regulators were not of a standard construction but were specially designed in that they were provided with very small, special shaft ball bearings, and were further provided with flexible leads instead of slip rings and brushes for the purpose of reducing friction losses to a minimum.

The principal use made of current transformers is in connection with relaying operations and measurements. For these uses current transformers of 100-volt ampere ratings are adequate, and consequently, current transformers in larger ratings are not built as a standard line of apparatus. Current transformers having ratings of the order of 3000-volt amperes were required for supplying the torque motor of a liquid slip regulator. Furthermore, it was necessary to design the current transformers specially to match the rating of the induction motor with which the regulator was used and the rating of the specially designed torque motor, with the result that a different transformer was required for each installation. Apparatus which is specially designed and constructed is more expensive than standard line apparatus which is produced in large quantities.

Another disadvantage of liquid slip regulators used heretofore was that the connections of the current transformer in the high voltage line to the induction motor with which the regulator was used made it necessary to house the transformer in an expensive metal-clad container, to maintain the standards of metal-clad construction.

Accordingly, a more specific object of this invention is the provision of a liquid slip regulator which is constructed of standard parts, such as small instrument type current transformers, direct current motors and excitors, thereby substantially to lessen the cost of the regulator without sacrificing anything in performance.

A further disadvantage of earlier slip regulators was the inconvenience of changing taps on the large current transformer or varying the counterweight to make adjustments for different

load settings, and a further object of this invention is the provision of a slip regulator in which such adjustments are made by varying a small potentiometer type resistor.

5 A still further disadvantage of slip regulators used heretofore was the necessity of providing an auxiliary motor in addition to the alternating current torque motor and an auxiliary weight in addition to the counterweight for raising the movable electrodes to the maximum resistance position prior to connecting the controlled induction motor to the source. Thus, a still further object of this invention is the provision of a control for a liquid slip regulator which eliminates 10 this auxiliary starting apparatus and provides for the utilization of the regulating torque motor to raise the movable electrodes to effect the maximum separation prior to connecting the controlled motor to the source.

20 In carrying the invention into effect in one form thereof, a direct current motor of a conventional design is provided for moving the movable electrodes. It is supplied from a conventional motor generator set of which the generator voltage is varied by means of an exciter which is excited by means of a conventional, small instrument type current transformer in the primary circuit of the controlled induction motor. This current transformer may be one which is being 25 utilized in connection with measurements or relaying operations.

If desired, the exciter may be a high speed, armature reaction excited machine. This type of exciter is also of a standard design which is 30 made in large quantities at low cost.

For a better understanding of the invention, reference should now be had to the following specification and to the accompanying drawing of which the single figure is a simple, diagrammatical sketch of an embodiment of the invention.

Referring now to the drawing, the primary winding of a polyphase alternating current motor 10 which is illustrated as an induction motor 45 of the wound rotor type is supplied from a suitable polyphase source, such as represented by the three supply lines 11 to which the primary winding of the motor may be connected by suitable switching means which are illustrated as a circuit breaker 12. This circuit breaker may be, and preferably is, of the oil circuit breaker type. The motor 10 is provided with a flywheel 13 of 50 suitable dimensions.

The peak demand of the induction motor 10 55 is to be limited by automatically inserting re-

sistance in the secondary circuit of the motor. This reduces the speed and permits the stored energy in the flywheel to carry the peak load. When the demand subsides, the induction motor accelerates and again stores energy in the flywheel.

For the purpose of inserting resistance in the secondary circuit of induction motor 10, a liquid rheostat 14 is provided. This liquid rheostat 14 comprises a tank 15 which contains a solution of sodium carbonate and a plurality of stationary electrodes 16, 17, and 18 and a plurality of cooperating movable electrodes 19, 20, and 21. The stationary electrodes 16, 17, and 18 are mounted within the tank at the bottom thereof. The upper or movable electrodes are fastened to a crossarm 22 which constitutes the Y-point of the secondary circuit.

To the top of the tank 15 is secured a suitable truss-shaped superstructure 23 upon which a pulley 24 is rotatably mounted in a position above the crossarm 22. A cable 25 is fastened to the crossarm 22. This cable passes over the pulley 24 and about a drum 26 to a counterweight 21. The weight of the electrodes 19, 20, and 21 and the crossarm supporting structure is such as to overbalance the counterweight 21 and move to the bottom of the tank to reduce the secondary resistance in the circuit of motor 10.

For the purpose of raising the movable electrodes to increase the resistance of the liquid rheostat, a direct current torque motor 28 is provided. This motor is supplied from an adjustable voltage direct current generator 29 which is driven at a speed which is preferably substantially constant by suitable means, such as an induction motor (not shown). The armatures of the torque motor 28 and the adjustable voltage generator 29 are connected in a direct loop circuit, as indicated in the drawing. The torque motor 28 is provided with a separately excited shunt field winding 28a which is supplied from a suitable source of excitation (not shown). The generator 29 is also provided with a separately excited field winding 29a. Variable excitation is supplied to this field winding 29a by means of a suitable exciter, such as the armature excited dynamoelectric machine 30. This machine is driven at a speed which is preferably substantially constant by any suitable driving means such as an induction motor (not shown).

The armature reaction excited machine 30 is provided with a pair of load brushes 30a and a pair of short-circuited brushes 30b which are arranged on an axis which is displaced 90 electrical degrees from the axis of the load brushes. The dynamoelectric machine 30 is provided with a plurality of control field windings 30c, 30d, and 30e. The control field winding 30c is supplied from a suitable source of excitation represented by the supply lines 31 and 32. This source may be, and preferably is, the same source as that from which the field winding 28a of the torque motor is supplied. The polarity of the excitation of the control field winding 30c is such that the excitation supplied by the dynamoelectric machine 30 to the field winding 28a causes the generator 29 to supply current to the torque motor 28 in a direction which causes the torque motor 28 to tend to raise the electrodes 19, 20, and 21. The field winding 30c is referred to as the bias field winding.

The field winding 30d is excited from the terminals of the adjustable voltage generator 29

to which it is connected by means of conductors 34 and 35. Thus, the control field winding 30d is responsive to the voltage of the generator 29 and is referred to as the voltage control winding. A plurality of resistors 36, 37, 38, and 39 are connected in series relationship with the voltage field winding 30d. The connections of the voltage field winding 30d to the terminals of the generator 29 are such that the voltage winding 30d opposes the bias field winding 30c.

The field winding 30e is excited in accordance with the load current of the main wound rotor induction motor 10. This is accomplished by connecting the field winding 30e to the output terminals of a rectifier 40, of which the input terminals are connected to the terminal 41a and the slider 41b of a potentiometer 41 which is connected across the secondary winding 42 of a current transformer, of which the primary winding 20 carries the load current supplied to one phase of the primary winding of the motor 10. Since the control field winding 30c is excited in accordance with the load current supplied to the induction motor 10, it is referred to as the load control field winding. The polarity of the load control field winding 30e is the same as the polarity of the bias control field winding 30c.

The armature reaction along the load brush axis is neutralized by means of a series compensating field winding 30f. The net excitation along the load brush axis produced by the control field windings produces a flux which causes current to flow in the short circuit. This short circuit current produces an armature flux which generates a voltage across the load brushes 30a and causes current to flow in the load circuit. The machine is thus a cross armature flux excited direct armature flux compensated dynamoelectric machine. The important characteristics of this machine are its high speed of response and its high amplification factor, i. e., the ratio of the current in the load circuit to the current in the control field windings.

The value of the load current supplied to the induction motor 10 can be adjusted by adjustment of the potentiometer 41.

The raising of the movable electrodes 19, 20, and 21 prior to the closing of the main circuit breaker 12 to start the induction motor 10 is under the control of a manually operated switching device 43 and a relay 44 which is directly controlled by the manually operated switching device 43. A limit switch 45 on the liquid rheostat and a relay 46 controlled thereby cooperate with the manually operated switching device 43 to close the main circuit breaker 12 to connect the induction motor 10 to the source.

The opening of the circuit breaker 12 to disconnect the motor 10 from the source is also under the control of the manually operated switching device 43.

For the purpose of rapidly braking the induction motor 10 to rest after it has been disconnected from the supply source 11, means are provided for producing a dynamic braking torque. These means are illustrated as a circuit breaker 47 which, when operated to its closed position, connects two phases of the induction motor 10 to a D.-C. source. The closing of the dynamic braking circuit breaker 47 is under the control of a manually operated switching device 48, a relay 49 controlled thereby, and contacts on the limit switch relay 46.

With the foregoing understanding of the ele-

ments and their organization, the operation of the liquid slip regulator to limit the load current supplied to the main induction motor 10 to a predetermined maximum value will readily be understood from the following detailed descriptions:

When the induction motor 10 is at rest, the movable electrodes 19, 20, and 21 are in their lowermost position in the tank 15, and the resistance of the secondary circuit of the induction motor 10 is a minimum. With the main oil circuit breaker 12 in the open position and the manually operated switching device 43 in the off position as illustrated in the drawing, the relay 50 is energized and picked up. The energizing circuit for the operating coil of this relay is traced from one side of a D.-C. source which may be, and preferably is, the same as that represented by the two supply lines 31 and 32, through normally closed interlocks on the circuit breaker 12, operating coil of the relay 50 to the negative side of the D.-C. supply source. Responsively to energization, the relay 50 closes its upper and lower normally open contacts 50a and 50b and opens its normally closed contacts 50c. Contacts 50a in closing complete the connections of the bias field winding 30c of the armature reaction excited dynamoelectric machine 30 to the source 31, 32, and the contacts 50b, in closing, short-circuit the resistor section 39 in the circuit of the voltage field winding 30d. The opening of contacts 50c inserts the adjustable resistor section 36 in the circuit of the voltage field winding 30d. The resistor sections 37 and 38 in the circuit of the voltage field winding 30d are short-circuited by the normally closed contacts 44a of relay 44. Thus, the resistor 36 is the only resistance in the circuit of the voltage field winding at this instant.

The excitation of the bias field winding 30c causes the exciter machine 30 to supply a voltage to the separately excited field winding 29a of the adjustable voltage generator 29. As the voltage of the generator 29 increases, the voltage field winding 30d which is excited differentially with respect to the field winding 30c increases until a condition of balance is reached such that any further increase in the excitation of the field winding 30d would tend to reduce the excitation of the adjustable voltage generator 29. When this condition of balance is reached, the adjustable voltage generator 29 supplies approximately 80 per cent of normal full load current to the armature of the torque motor 28. At this value of armature current, the torque developed by the torque motor 28 is insufficient to raise the electrodes 19, 20, and 21.

To raise the electrodes and connect the induction motor 10 to the source 11, the manually operated switching device 43 is moved from the central off position to the closed position at the right. In this position, the movable contact members 43a and 43b engage the stationary contact members 43c and 43d respectively. The engagement of contacts 43b and 43d completes an energizing circuit for the operating coil of the relay 44 which picks up and closes its upper normally open contacts 44b to short-circuit the adjustable resistor 36 and opens its lower normally closed contacts 44a to insert the resistor sections 37 and 38 in the circuit of the voltage field winding 30d. The short circuiting of the resistor section 36 tends to strengthen the voltage field 30d, but the insertion of the resistors 37 and 38 weakens the field more than it is strengthened. Thus,

the opposing effect of the field winding 30d is lessened, and the net excitation of the armature excited dynamoelectric machine 30 is increased. As a result, the voltage of the adjustable voltage generator 29 is further increased, and the current which is supplied to the torque motor 28 is correspondingly increased. The increasing voltage of the generator 29 also increases the excitation of the opposing voltage field winding 30d until a new condition of balance is established. This new condition of balance is reached when the voltage of the generator 29 is such that approximately 100 per cent of full load current is supplied to the torque motor 28.

15 The torque developed by the torque motor 28 at 100 per cent full load current, together with the torque produced on the drum 26 by the counterweight 27, is sufficient to raise the movable electrodes 19, 20, and 21 and as a result, the movable electrodes are moved toward the upper or maximum resistance position.

20 When the electrodes reach their upper or maximum resistance position, the limit switch 45 closes the normally open contacts 45a to complete an energizing circuit for the operating coil of the limit switch relay 46. The relay 46 in picking up closes its normally open contacts 46a, 46b, and 46c. The contacts 46a in closing complete an energizing circuit for the operating coil of

30 relay 51. As illustrated, this relay is provided with an adjustable time delay device such as the dashpot 51a which introduces a time delay in the dropout of relay 51 but permits it to pick up without time delay. Consequently, the relay 51 picks up without time delay and closes its normally open contacts 51b to complete an energizing circuit for the operating coil 12a of the circuit breaker 12. In response to energization, the circuit breaker 12 closes its main contacts to connect the primary winding of the induction motor 10 to the supply source 11 and simultaneously opens its auxiliary interlock contact 12b. Circuit breaker 12 in closing latches itself in the closed position by means of latching mechanism

45 12c. Contacts 12b in opening interrupt the energizing circuit for the operating coil of the relay 51 which after a time interval determined by the adjustment of the time delay device 51a drops out and opens its main contacts 50b to interrupt the energizing circuit for the operating coil 12a of circuit breaker 12. The circuit breaker, however, is held closed by the latching mechanism 12c. The manually operated switching device 43 may now be released, and its centering springs 55 return it to the central or off position.

Contacts 12b of the circuit breaker 12 in opening also interrupt the energizing circuit for the operating coil of relay 50. In response to de-energization, relay 50 drops out and opens its

60 normally open contacts 50a and 50b and closes its normally closed contacts 50c. The opening of contacts 50b inserts resistor 39 in circuit with the voltage control field winding 30d, and the closing of contacts 50c short-circuits resistor section 36. The opening of contacts 12b also inter-

65 rupts the energizing circuit for the operating coil of relay 44 which drops out to close its normally closed contacts 44d and to open its normally open contacts 44b. Contacts 44d in closing short circuit resistor sections 38 and 39. Thus at this instant only the resistor section 39 is in circuit with the voltage control field winding.

70 The opening of contacts 50a disconnects the bias control field winding 30c from the source 31, 32. Simultaneously, however, the load field

winding 30e is energized by a current which is proportional to the current supplied from the source 11 to the primary winding of the induction motor 10. Since the inrush current to the motor 10 is limited by the maximum resistance of the liquid rheostat 15, the current supplied to the load field winding 30 is a minimum. Consequently, the net excitation of the armature reaction excited dynamoelectric machine 30 is decreased and this results in decreasing the current supplied to the torque motor 28 below the value which is sufficient to maintain the movable electrodes 19, 20, and 21 in the upper limit position. As a result, the movable electrodes 19, 20, and 21 start to descend. As the separation between the movable electrodes and the stationary electrodes decreases, the resistance in the secondary circuit of the induction motor 10 is correspondingly decreased, and the current taken by the primary winding from the source 11 is correspondingly increased.

At a predetermined value of load current taken by the induction motor 10, which value is determined by the position of the slider 41b on the potentiometer 41, a condition of balance is reached in which the exciting current supplied to the load field winding 30e increases the net excitation of the dynamoelectric machine 30 to a value at which the torque developed by the torque motor 28 is sufficient when added to the pull of the counterweight 27 to arrest the descent of the movable electrodes.

The induction motor 10 is accelerated by this maximum value of current which can be taken from the supply source 11 and as it accelerates, it stores energy in the flywheel 13.

As long as the demand of the load on the induction motor 10 remains less than the maximum load as determined by the setting of the potentiometer 41, the motor drives the load without taking any energy from the flywheel 13. Consequently, if the peak demand of the load is greater than the value of maximum load current determined by the setting of the potentiometer 41, the tendency of the induction motor 10 is to decrease its speed and draw more current from the line. The increase in current immediately strengthens the net excitation of the dynamoelectric machine 30 and ultimately, the torque of the torque motor 28. In response to the increased torque of the torque motor, the movable electrodes 19, 20, and 21 are moved upward to increase the resistance in the secondary circuit of the induction motor 10, and prevent the induction motor 10 from drawing more than the predetermined maximum value of current from the line 11. Consequently, the speed of the induction motor 10 decreases and the flywheel 13 then carries the load at the decreased speed.

When the load on the induction motor 10 decreases, the opposite action results. As the torque of the torque motor 28 decreases, the movable electrodes descend toward the stationary electrodes, thereby cutting out resistance. Thereupon, the speed of the induction motor 10 increases so that the stored energy given up by the flywheel is again restored to the flywheel. This action is repeated whenever the load imposed on the shaft of the induction motor 10 exceeds the maximum load current setting of the potentiometer 41.

In order to minimize overshooting or hunting of the regulator, suitable antihunt means are provided. This means comprises a transformer 52 having its primary winding 52a connected

across the load brushes 30a of the armature reaction excited dynamoelectric machine 30 and having its secondary winding connected in a parallel loop circuit with the bias control field winding 30c. Thus, when the voltage supplied to the torque motor 28 by generator 29 is changing as a result of a change in the output voltage of dynamoelectric machine 30, a voltage which is proportional to the rate of this change is induced in the secondary winding 52b of transformer 52. This secondary induced voltage is supplied to the bias control field winding 30c in a direction which opposes the change. As a result, the rate of change of the output voltage of dynamoelectric machine 30 is decreased before the final value is attained, and thus, overshooting or hunting is substantially eliminated.

To stop the motor 10, the manually operated switching device 48 is rotated counterclockwise from the central position to the trip position. In this position, an energizing circuit is completed for the operating coil of the tripping relay 53. In response to energization, the core of relay 53 is moved upward to release the latching mechanism 12c and allow the spring 12d to open the circuit breaker 12 and thereby disconnect the motor 10 from the supply source 11.

In the open position of circuit breaker 12, an energizing circuit is completed for the operating coil of relay 50 through the normally closed interlock contacts 12b. Responsively to energization, relay 50 closes its contacts 50a and 50b and opens contacts 50c. Contacts 50a in closing reconnect the bias control field winding 30c to the supply source 31, 32. At this time the load control field winding 30e is deenergized owing to the disconnection of motor 10 from the source 11. Contacts 50b in closing short-circuit the resistor 38 in the circuit of the voltage control field winding 30d of dynamoelectric machine 30. Since the resistors 37 and 38 are short-circuited by the contacts 44a of relay 44, the voltage control field winding 30d is strengthened to a value at which it overpowers the bias control field winding 30c. As a result, the output voltage of the dynamoelectric machine 30 is reversed. This reversal of the output voltage of dynamoelectric machine 30 forces the excitation of generator 29 to decrease very rapidly. As the voltage of generator 29 decreases, the current supplied to the torque motor 28 and the torque developed thereby decrease correspondingly. As a result, the pull of the counterweight 27 plus the decreased torque of the torque motor 28 is no longer sufficient to maintain the electrodes 19, 20, and 21 in a raised position, and consequently, they descend to the minimum resistance position at the bottom of the tank.

As the voltage of the generator 29 decreases, the excitation of the voltage control field winding decreases so that the polarity of the output voltage of the armature reaction excited dynamoelectric machine is again determined by the bias control field winding 30c.

If it is desired to brake the induction motor 10 rapidly to rest, the manually operated switching device 48 is rotated in a clockwise direction to the closed position. In this position, energizing circuits are established for the operating coils of relays 44 and 49. In response to energization, relay 44 picks up to open its contacts 44a and close its contacts 44b. In closing, the contacts 44b short-circuit the resistor 36, thereby tending to strengthen the voltage field 30d, but contacts 44a in opening insert the resistors

37 and 38 and weaken the voltage field more than it is strengthened. As a result, the net excitation of the dynamoelectric machine 30 is increased, and the voltage supplied to the field winding 29a of generator 29 is correspondingly increased until a condition of balance is reestablished. The increasing excitation of generator 29 increases the voltage and current supplied to the torque motor 28, thereby causing motor 28 to raise the electrodes 19, 20, and 21 to the upper maximum resistance position. In this position, the limit switch 45 closes its contacts 45a to complete an energizing circuit for the operating coil of the limit switch relay 46 which picks up and closes its contacts 46a, 46b, and 46c. Contacts 46b in closing complete an energizing circuit for the operating coil of the dynamic braking relay 49 which in response to energization picks up and closes its contacts to complete an energizing circuit for the operating coil of the dynamic braking circuit breaker 47. In response to energization, dynamic braking circuit breaker 47 closes its contacts to connect a portion of the primary winding of induction motor 10 to a source of direct current excitation. This direct current excitation of a portion of the induction motor winding produces a large braking torque which rapidly brakes the induction motor to rest. It will be noted that the switching device 48 need only be held in the closed position momentarily to allow the latching mechanism 47a to latch the dynamic braking circuit breaker 47 in the closed position.

After the induction motor 10 has been braked to rest, the primary winding of the induction motor may be disconnected from the source of direct current excitation by rotating the manually operated switching device in a counterclockwise direction to complete an energizing circuit for the operating coil of the trip relay 47b. This relay in response to energization releases the latching mechanism 47a, thereby allowing the circuit breaker 47 to drop to the open position.

Although in accordance with the provisions of the patent statutes this invention is described as embodied in concrete form and the principle thereof has been explained, together with the best mode in which it is now contemplated applying that principle, it will be understood that the apparatus shown and described is merely illustrative and that the invention is not limited thereto, since alterations and modifications will readily suggest themselves to persons skilled in the art without departing from the true spirit of this invention or from the scope of the annexed claims.

What I claim as new and desire to secure by Letters Patent of the United States is:

1. A liquid slip regulator for an induction motor comprising a tank containing an electrolyte and relatively movable electrodes connected in circuit with said motor, a direct current motor for varying the separation of said electrodes, an adjustable voltage generator for supplying said motor, means for exciting said generator comprising a dynamoelectric machine provided with a load control field winding, and means responsive to the current supplied to said alternating current motor for exciting said control field winding.

2. A liquid slip regulator for an induction motor comprising a tank containing an electrolyte and relatively movable electrodes connected in circuit with said motor, a direct current motor for varying the separation of said electrodes, an

adjustable voltage generator for supplying said motor, means for exciting said generator comprising a dynamoelectric machine provided with a load control field winding, and means for supplying to said control field winding a direct voltage derived from the alternating current supplied to said induction motor.

3. A liquid slip regulator for an alternating current motor comprising in combination a tank containing an electrolyte and a plurality of relatively movable electrodes in circuit with said motor, a direct current motor for varying the separation of said electrodes, an adjustable voltage generator for supplying said direct current motor, means for exciting said generator provided with a load control field winding and an opposing field winding energized by the voltage of said generator, and means for supplying to said control field winding a direct voltage derived from the current supplied to said alternating current motor.

4. A liquid slip regulator for an alternating current motor comprising in combination a tank containing an electrolyte and a plurality of relatively movable electrodes in circuit with said motor, a direct current motor for varying the separation of said electrodes, an adjustable voltage generator for supplying said direct current motor, means for exciting said generator comprising a dynamoelectric machine provided with a separately excited field winding and an opposing field winding energized by the voltage of said generator, a switching device, and means responsive to operation of said switching device for weakening the excitation of said opposing field winding to increase the voltage of said generator thereby to cause said motor to separate said electrodes.

5. A liquid slip regulator for an induction motor comprising in combination a tank containing an electrolyte and a plurality of relatively movable electrodes in circuit with said motor, a direct current motor for varying the separation of said electrodes, an adjustable voltage generator for supplying said direct current motor, means for exciting said generator comprising a dynamoelectric machine provided with a separately excited control field winding, an opposing control field winding excited by the voltage of said generator, and a load control field winding excited by a current derived from the current supplied to said induction motor, a switching device, means responsive to operation of said switching device for weakening said opposing field to strengthen the voltage of said generator and cause said direct current motor to separate said electrodes, and limit switch means responsive to a predetermined separation of said electrodes for deenergizing said separately excited field winding and for connecting said induction motor to a source of alternating current.

6. A liquid slip regulator for an induction motor comprising in combination a tank for containing an electrolyte and a plurality of relatively movable electrodes, a direct current motor for varying the separation of said electrodes, an adjustable voltage generator for supplying said direct current motor, means for exciting said generator comprising a dynamoelectric machine provided with a separately excited control field winding, an opposing field winding excited by the voltage of said generator and a load control field winding, a current transformer energized by the load current of said induction motor, and a rec-

tiflier in circuit with said transformer for exciting said load control field winding in the same direction as said separately excited field winding, a switching device, means responsive to operation of said switching device for varying the relative excitations of said separately excited and opposing control field windings to increase the voltage of said generator to cause said motor to separate said electrodes, and limit switch means responsive to a predetermined separation of said electrodes for deenergizing said separately excited field winding and connecting said induction motor to an alternating current source to provide for excitation of said dynamoelectric machine by the differential effect of the load on said induction motor and the voltage of said generator.

7. A liquid slip regulator for an induction motor comprising in combination an electrolyte container, a plurality of relatively movable electrodes within said container, a direct current motor for varying the separation of said electrodes, an adjustable voltage generator for supplying said direct current motor, means for exciting said generator comprising a dynamoelectric machine provided with a control field winding connected to be excited by a direct voltage derived from the alternating current supplied to said induction motor and an opposing field winding excited by the voltage of said generator to cause said motor to vary the separation of said electrodes to limit the current supplied to said induction motor to a predetermined value, and means for adjusting said derived voltage to a value corresponding to a desired limiting value of current supplied to said induction motor.

8. A liquid slip regulator comprising in combination, an electrolyte container, a plurality of relatively movable electrodes within said container, a direct current motor for varying the separation of said electrodes, an adjustable voltage generator for supplying said direct current motor, means for exciting said generator comprising a dynamoelectric machine provided with a separately excited field winding and an opposing field winding excited by the voltage of said generator to effect energization of said generator of a polarity to cause said motor to effect separation of said electrodes, and a transformer having its primary winding connected across said generator and its secondary winding connected in circuit with said separately excited field winding to minimize hunting action of said slip regulator.

9. A liquid slip regulator for an induction motor comprising in combination an electrolyte con-

tainer, a plurality of relatively movable electrodes within said container, a direct current electric motor for varying the separation of said electrodes, an adjustable voltage generator for supplying said motor, means for exciting said generator comprising a dynamoelectric machine provided with a separately excited control field winding, an opposing control field winding excited by the voltage of said generator and a load control field winding excited by a current derived from the current supplied to said induction motor and having the same polarity as said separately excited field winding, a switching device, means responsive to operation of said switching device for weakening said opposing field to cause said direct current motor to separate said electrodes, limit switch means responsive to a predetermined separation of said electrodes for deenergizing said separately excited field winding and connecting said induction motor to an alternating current source so that said load control field winding and said opposing control field winding control said dynamoelectric machine to limit the current supplied to said induction motor to a predetermined value, and a transformer having its primary winding connected across said generator and its secondary winding connected to said separately excited field winding to minimize hunting action of said regulator.

10. A liquid slip regulator for an induction motor comprising in combination, an electrolyte container, a plurality of electrodes within said container, a direct current motor for varying the separation of said electrodes, an adjustable voltage generator for supplying said direct current motor, means for exciting said generator comprising a dynamoelectric machine provided with a load control field winding connected to be excited in response to a voltage derived from the current supplied to said induction motor, an opposing control field winding excited in response to the voltage of said generator and a separately excited field winding, means for deenergizing said induction motor to effect stopping thereof, a switching device, means responsive to operation of said switching device for connecting said separately excited field winding to a source of excitation and weakening the strength of said opposing control field winding to cause said direct current motor to rotate to separate said electrodes, and limit switch means responsive to a predetermined separation of said electrodes for supplying direct current to a winding of said induction motor to effect dynamic braking thereof.
